(57) **CLAIM**

The ornamental design for a camera, as shown and described.

DESCRIPTION

FIG. 1 is a front, left, and top perspective view of a camera showing our new design;

FIG. 2 is a front, right, and bottom perspective view thereof;

FIG. 3 is a rear, right, and bottom perspective view thereof;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a top plan view thereof; and,

FIG. 9 is a bottom plan view thereof.

The dot-dashed broken lines shown on the camera illustrate boundary lines and form no part of the claimed design. The even dashed broken lines shown in the drawings represent portions of the camera that form no part of the claimed design.

1 Claim, 7 Drawing Sheets
